DESIGN FOR A DRESS

Samuel Zahn, New York, N. Y.

Application July 29, 1940, Serial No. 94,021

Term of patent 3½ years

To all whom it may concern:

Be it known that I, Samuel Zahn, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

The characteristic feature of my design resides in the combination on the dress disclosed of the fan-shaped shirring at the shoulders in association with the pleated skirt and the shirring at the cuff of the sleeve members, all as shown.

I claim:

The ornamental design for a dress, substantially as shown and described.

SAMUEL ZAHN.
